BOTTLE OR SIMILAR ARTICLE

Filed Feb. 25, 1935

FIG. 1.

FIG. 2.

Inventor
Joseph S. Stein.

by Charles Marshall Atty.

UNITED STATES PATENT OFFICE

95,873

DESIGN FOR A BOTTLE OR SIMILAR ARTICLE

Joseph S. Stein, Chicago, Ill., assignor to Lucien Lelong, Inc., Chicago, Ill., a corporation of Illinois

Application February 25, 1935, Serial No. 55,604

Term of patent 7 years

To all whom it may concern:

Be it known that I, Joseph S. Stein, a citizen of the United States, and a resident of the city of Chicago, county of Cook, and State of Illinois, have invented a new, original, and ornamental Design for a Bottle or Similar Article, of which the following is a specification, reference being had to the accompanying drawing, forming a part thereof.

On the drawing:

I claim:

The ornamental design for a bottle or a similar article, as shown.

JOSEPH S. STEIN.
